CLAIM

The ornamental design for a display screen with graphical user interface for workflow, as shown and described.

DESCRIPTION

FIG. 1 is a first view of a display screen with graphical user interface for workflow; and,
FIG. 2 is a second view of a display screen with graphical user interface for workflow.

The appearance of the transitional image sequentially transitions between the images shown in FIGS. 1-2. The process or period in which one image transitions to another image

The broken lines showing the display screen are for environmental purposes only and form no part of the claimed design.
